UNITED STATES PATENT OFFICE.

GUSTAVUS A. MONTGOMERY, OF OILFIELDS, CALIFORNIA.

UNDERREAMER.

1,087,812.

Specification of Letters Patent. Patented Feb. 17, 1914.

Application filed May 10, 1913. Serial No. 766,842.

To all whom it may concern:

Be it known that I, GUSTAVUS A. MONTGOMERY, a subject of Emperor of Russia, and a resident of Oilfields, in the county of 5 Fresno and State of California, have invented a new and Improved Underreamer, of which the following is a full, clear, and exact description.

My invention relates to an under reamer 10 to be employed for enlarging a drill hole previously formed with an ordinary club bit in drilling for crude oil.

Objects of my invention are to provide an under reamer that may be readily repaired 15 at small cost; to provide a large area of wearing surfaces between the cutters and their supporting elements; to provide a construction in which the wearing surfaces will be to a large extent protected against the 20 entrance of abrasive matter; to provide perfect seats for the cutters; to make provision for preventing the losing of the reamer cutters; to promote convenience in adjusting the reamer in position to be lowered into 25 the well; and to provide an under reamer, the body of which shall be free from sub-joints.

It is also a design of my invention to improve in various particulars, devices of the 30 general character indicated, to the end that strength may be promoted, as well as efficiency in operation, economy of manufacture, and simplicity of adjustment and control.

The distinguishing features of the invention, and the important structural elements characterizing the preferred embodiment 35 which is illustrated as an example, will be more particularly explained in the specific 40 description following.

Reference is to be had to the accompanying drawings forming a part of this specification, in which similar characters of reference indicate corresponding parts in all 45 the views.

Figure 1 is a vertical section of an under reamer embodying my invention, the reamer cutters being in the contracted positions to be lowered into the well; Fig. 2 is 50 a side elevation with parts in section, on the line 2-2 of Fig. 1; Fig. 3 is a vertical section on an enlarged scale of a portion of the reamer, the cutters being in the expanded position; Figs. 4 and 5 are cross sections on 55 an enlarged scale on approximately the lines 4-4 and 5-5 of Fig. 1; and Fig. 6 is an

enlarged side elevation of the removable core hereinafter particularly referred to.

In constructing a reamer in accordance with the illustrated example, a body 10 is 60 provided, which terminates at its lower end in a shell 11 that receives the upper end of a removable core 12. The lower end of the body 10 has an axial bore 13, and a registering bore 14 is formed in the core 12, the 65 lower end 14^a of the bore 14 being of reduced diameter to present an internal shoulder.

Movable axially in the bores of the body 70 and core is a spindle 15, which carries at its lower end expanding cutters 16. The connection between the cutters and spindle is effected by a key 17 which is received in a transverse slot 18 in the spindle, there being a slot 19 in the core registering with the 75 slot 18, and of greater length than the latter, to permit vertical movement of the key in response to up and down movements of the spindle, as hereinafter referred to. The key at its ends is received also in transverse slots 20 formed in the shanks 16^a of the cutters 16, whereby the cutters will be 80 raised and lowered. The bits of the cutters, it will be observed, are offset from the shanks.

The core 12 is formed at the ends of its 85 slots 19 with recesses, the bottom surfaces 21 of which constitute seats for the shanks of the cutters, the said seats and the opposed surfaces of the shanks presenting mating 90 inclines. I provide means to expand the cutters in their upward movement, while in the downward movement of the cutters they will be caused to contract and move inwardly toward each other.

To force the spindle downward for moving the cutters, a wedge 22, indicated in dotted lines in Fig. 2, is employed, which is adapted to be passed through a transverse slot 23 transecting the bore 13, at the upper 10 end of the latter, so that the wedge may engage the upper end of the spindle and force the same downwardly against the tension of a helical compression spring 24 which surrounds the spindle. The upper end of 10 the spring seats against a shoulder provided on the spindle as by a washer 15^a and nut or head 15^b, while the lower end of the spring seats on the shoulder provided by the reduced bore 14^a of the core. The tendency of 11 the spring therefore is to lift the spindle and thereby draw the cutters upwardly. The

head 15^b has a groove 15^c to receive the key 22, and when said groove is in line with slot 23, the slots 19, 20 will also align with each other and will align with slot 28 in the shell 11 when at the level of the latter.

5 I provide latching members so that the cutters will be held latched when in the lowered position against the lifting action of the spring 24, for which purpose use is made 10 of mating shoulders on the core and cutters respectively. Thus a shoulder or horizontal surface 12^c is presented at the lower end of the inclined seat surfaces 21, and mating shoulders 16^b, best seen in Fig. 3, are formed 15 on the opposed faces of the shanks 16^a of the cutters. To guide the cutters and give them a lateral movement when raised and lowered by the spindle for expanding and contracting the reamer, co-acting guide elements are 20 provided on the core and cutters. Thus, as seen best in Figs. 3 and 5, the cutters are formed with inclined grooves 25; and pins 26, preferably in the form of screw-studs, are provided on the core, which enter the 25 said grooves.

By the described construction it will be seen that when the spindle is forced downwardly by a wedge 22, the spring 24 will be placed under tension, and the spindle 30 through the action of the key 17, will carry the cutters downwardly, the action of the pins 26 and grooves 25 giving a lateral movement to the cutters and causing the same to move downwardly and inwardly, 35 following the inclined seat surfaces 21 until the shoulders 16^b of the cutters arrive below the shoulder 12^c of the core 12, permitting the cutters to swing into latching engagement with the core, as shown in Fig. 1. 40 Upon the pressure on the spindle and pin being relieved by the withdrawal of the wedge 22, the spring will have a tendency to draw the spindle and cutters upwardly, but it will be resisted by the latched engagement of the described shoulders until the 45 reamer is lowered into the well. When the cutter bits emerge from the usual casing (not shown), they may expand as the point of engagement with key 17 results in sufficient leverage to disengage the shoulders and permit the expansion when the outward movement is not restrained by the casing.

The shell 11 depending from the body 10 is integral with the latter in the preferred 55 construction, and therefore the body of the reamer is free from sub-joints. For the insertion and removal of the key 17, a slot 28 is formed in the shell 11, and the spindle may be so moved as to temporarily bring the 60 key-slots in the spindle, core and cutter shanks in line with said slot 28. The construction of the tool guards against the loss of the cutters by displacement of the key, since at no time will the key be in register 65 with the slot 28 except for the briefest

period in the up and down movements of the cutters; but if desired, the slot 28 may have a formation to receive a screw plug 29 to prevent any possibility of the key escaping laterally.

70 The lower end of the core at opposite sides of the cutters extends as at 12^b below the lower edge of the shell 11 so as to afford an increased brace to the cutters. By reason of the inclined contact surfaces between the 75 core and cutters, the latter will have a perfect seat, wedging themselves into position in response to the upward force of the spring, and therefore when in use, the cutters instead of becoming loose will tend to 80 seat themselves more firmly. It will be obvious, furthermore, that the described arrangement provides a very broad surface contact between the cutters and their seats, for distributing the wear, and moreover, the 85 shell 11 provides a housing, the lower edge of which will be adjacent to the upper edges of the bits when the latter are in the working position, the arrangement minimizing the tendency of sand or grit to enter between 90 the wearing surfaces of the cutter shanks and their seats. Provision, however, may be made for the escape of any grit from the shell, such for instance as the formation of clearance holes 30 in the shell 11. A hole 9 30^c diametrically opposite slot 28 permits entrance of a tool to drive out the key 17.

95 The connection between the core and shell may be effected in any approved manner, advantageously by forming a thread of coarse 1 pitch, as at 12^a, on the upper end of the core to engage corresponding threads in the interior of the shell, and a pin 31 may be provided additionally, to pass through the shell and core.

100 The removable core permits of repairs being made with convenience and despatch and at small cost. Should the efficiency of the tool be impaired by wear between the cutters and core, the core may be removed 1 and planed down, and shortened if necessary, without the necessity of discarding it, thus prolonging the life of the core at small cost. Even the total replacing of the core 1 will cost but little. Moreover, should the shell of the body be impaired by use it may be cut off at its lower end to correspond with any shortening of the cutter shanks and core, the original manufactured length making provision for this change.

Having in mind the possible breaking of the cutters which would occur, if at all, at the juncture of the bits and shanks, I provide bolts or pins 27 ranging lengthwise in the cutters from the shoulders 16^b downwardly to the inner faces of the bits, the latter having recesses 16^a to receive the bolt heads. The pins it will be seen range in the cutters across the juncture of the shanks and bits so that if a break occurs at this

point, the broken parts will be held together and will be drawn upwardly with the reamer.

It is to be understood that the under 5 reamer operates in the same manner as others, the cutter bits being positioned below the drive pipe shoe (not shown).

Having thus described my invention, I 10 claim as new, and desire to secure by Letters Patent:

1. An under reamer, comprising a body, reamer cutters, a member at the lower end of the body providing seats for the cutters, and relatively to which the cutters may be 15 raised and lowered, said member having a portion between the cutters with which the latter have latching engagement when lowered, spring-pressed means tending to raise said cutters, and means for guiding 20 the cutters into the mentioned latching engagement when moved in opposition to the spring pressure.

2. An under reamer, comprising a body, a depending member at the lower end of the 25 body presenting oppositely inclined seats, reamer cutters presenting inclines corresponding with said seats, means for raising and lowering the cutters, and co-acting means on the said depending member and 30 on the reamer cutters adapted for latching engagement when the cutters are moved to the lowered position.

3. An under reamer comprising a body, a removable depending core at the lower end 35 of the body, reamer cutters seating on said core, the lower end of the core presenting a shoulder and the cutters having opposite shoulders to engage said shoulder of the core, a spindle carrying said cutters and 40 movable longitudinally in the body and core, a coiled spring on said spindle tending to lift the same, and means for guiding the cutters into engagement with the shoulder of the core when they are carried downward by the spindle moving in opposition to 45 the spring.

4. An under reamer comprising a body having a depending shell terminating in an 50 open lower end, a depending core within the shell, there being spaces between the shell and core, expanding reamer cutters having bits below the lower edge of the shell and having shanks fitting in the spaces between the shell and core, the cutters being 55 movable to raise or lower the same, means for raising and lowering the cutters relatively to the core, and means to respectively expand and contract the cutters as they are raised and lowered, the reamers 60 in the lowered position having latching engagement with the core.

5. An under reamer, comprising a body terminating in a depending shell open at its lower end, a removable core held within said shell, expanding cutters fitting between the shell and core, an axially movable spindle in the body and core, and a transverse key carried by the spindle, said spindle being slotted to removably receive 65 said key, the core having a transverse slot of greater length than the slot of the spindle, reamer cutters having slots registering with those of the spindle and core, there being a slot in the shell, at one side, with which the slots in the spindle and cutters 70 may be brought into register for the entrance and removal of the key, the said shell presenting a closed wall to the ends of the key in both the lowered and raised positions of the key.

6. The herein described cutter for reamers having a bit and a shank, and a separate elongated element ranging lengthwise in the cutter across the junction of the shank and bit.

7. An under reamer, comprising a body terminating at its lower end in a depending shell, a core removably held to the body within the shell, the body having a bore and the core having a registering bore, a spindle in the said bores, a helical spring surrounding the spindle and tending to lift the same, there being a transverse slot in the body at the upper end thereof to receive a wedge to lower the spindle against the tension of the spring, said spindle having a transverse key-slot at its lower end and the core having a registering transverse slot of greater length than that of the spindle and having side recesses communicating 100 with the slots and forming seats, reamer cutters having slotted shanks receivable in the recesses of the core, between the latter and the shell, the said cutters and the seat surfaces of the core having mating inclines, 105 a transverse key removably fitting the slots of the spindle, core and cutter shanks, there being a slot in the shell for the entrance and removal of the key, and the core and shanks of the cutters having guide pins and 110 inclined guide grooves, the cutters furthermore having latching members engageable with the core and carried downward by a lowering of the spindle.

In testimony whereof I have signed my 115 name to this specification in the presence of two subscribing witnesses.

GUSTAVUS A. MONTGOMERY.
